FIG. 1

FIG. 2

FIG. 3

FIG. 1 is a top plan view of a warming stand embodying my design;

FIG. 2 is a front elevation thereof; and

FIG. 3 is a side elevation thereof.

My design for the warming stand disclosed is characterized by the specifically contoured unitary element thereof comprising handles and a dish support, together with the angled rods transversely disposed near the ends of the dish support portion of said unitary element.

I claim:

The ornamental design for a warming stand, as shown and described.
